FIG. 3 is a third view thereof;

FIG. 4 is a fourth view thereof;

FIG. 5 is a fifth view thereof;

FIG. 6 is a sixth view thereof;

FIG. 7 is a seventh view thereof; and

FIG. 8 is an eighth view thereof.

FIG. 9 is a front view of a second embodiment of a display panel or screen with a graphical user interface showing our new design;

FIG. 10 is a second view thereof;

FIG. 11 is a third view thereof;

FIG. 12 is a fourth view thereof;

FIG. 13 is a fifth view thereof;

FIG. 14 is a sixth view thereof;

FIG. 15 is a seventh view thereof; and

FIG. 16 is an eighth view thereof.

FIG. 17 is a front view of a third embodiment of a display panel or screen with a graphical user interface showing our new design;

FIG. 18 is a second view thereof;

FIG. 19 is a third view thereof;

FIG. 20 is a fourth view thereof;

FIG. 21 is a fifth view thereof;

FIG. 22 is a sixth view thereof;

FIG. 23 is a seventh view thereof; and

FIG. 24 is an eighth view thereof.

FIG. 25 is a front view of a fourth embodiment of a display panel or screen with a graphical user interface showing our new design;

FIG. 26 is a second view thereof;

FIG. 27 is a third view thereof;

FIG. 28 is a fourth view thereof;

FIG. 29 is a fifth view thereof;

FIG. 30 is a sixth view thereof;

FIG. 31 is a seventh view thereof; and

FIG. 32 is an eighth view thereof.

FIG. 33 is a front view of a fifth embodiment of a display panel or screen with a graphical user interface showing our new design;

FIG. 34 is a second view thereof;

FIG. 35 is a third view thereof;

FIG. 36 is a fourth view thereof;

FIG. 37 is a fifth view thereof;

FIG. 38 is a sixth view thereof;

FIG. 39 is a seventh view thereof; and

FIG. 40 is an eighth view thereof.

FIG. 41 is a front view of a sixth embodiment of a display panel or screen with a graphical user interface showing our new design;

FIG. 42 is a second view thereof;

FIG. 43 is a third view thereof;

FIG. 44 is a fourth view thereof;

FIG. 45 is a fifth view thereof;

FIG. 46 is a sixth view thereof;

FIG. 47 is a seventh view thereof; and

FIG. 48 is an eighth view thereof.

FIG. 49 is a front view of a seventh embodiment of a display panel or screen with a graphical user interface showing our new design;

FIG. 50 is a second view thereof;

FIG. 51 is a third view thereof;

FIG. 52 is a fourth view thereof;

FIG. 53 is a fifth view thereof;

FIG. 54 is a sixth view thereof;

FIG. 55 is a seventh view thereof; and

FIG. 56 is an eighth view thereof.

FIG. 57 is a front view of an eighth embodiment of a display panel or screen with a graphical user interface showing our new design;

FIG. 58 is a second view thereof;

FIG. 59 is a third view thereof;

FIG. 60 is a fourth view thereof;

FIG. 61 is a fifth view thereof;

FIG. 62 is a sixth view thereof;
